UNITED STATES PATENT OFFICE.

MAX SCHLING, OF NEW YORK, N. Y.

DANDELION KILLER.

Application filed September 30, 1925. Serial No. 59,598.

The invention relates to hand gardening implements, and is a device for expeditiously and effectively destroying dandelions or like weeds in lawns; and the object is to provide 5 a device of this character whereby a predetermined, small charge of poisonous liquid will be administered and confined directly to each plant selected for extermination.

In the accompanying drawings, forming 10 part thereof;

Fig. 1 is a longitudinal section through one form of the invention, showing parts in the plane of the section principally in elevation;

15 Fig. 2 is a sectional end view taken on the line 2—2 of Fig. 1;

Fig. 3 is a longitudinal section through another embodiment; and

20 Fig. 4 is an enlargement of the lower part of Fig. 3, showing the parts in another position.

The form of Figs. 1 and 2 will first be described. The device comprises a flask 2 of any suitable material to hold the liquid 25 adapted to be held in the hand, and having an outlet at its forward or lower end. In the axial opening 3 at the outlet end, there fits slidingly with a liquid-tight joint the forward end of a longitudinal rod 4, which passes through the flask and has an operating 30 button or handle 5 at its rear end. A cross hole 6 in the forward end of the rod forms a pocket calculated to hold the charge necessary for killing a plant.

35 When the rod is retracted, this pocket is brought into communication with the interior of the flask and becomes filled; and when the rod is released and is moved forward by a spring 7 the pocket is projected 40 outward as seen in Fig. 1 so that its charge is dropped upon the plant. The spring normally holds the rod in this position, the rod being retracted by the pull of the fingers of one hand, which secures a purchase on 45 a handle 8 on the rear end of the flask.

The outlet is surrounded by a rim or wall 9, of materially larger internal diameter than the rod 4 and opening 3. This rim has a beveled lower edge 10 and is adapted to be 50 pressed down and into the ground or plant

so as to form a poison-administering chamber, to enclose the deposited charge and keep it from spreading.

A plug 11 enables the flask to be refilled.

In the embodiment shown in Figs. 3 and 4 55 the flask 2^a has a fitting 12 screwed on its forward end, removal of which fitting permits refilling.

This fitting has a transverse guide-way 13, and ports 14 and 15 out of alinement 60 with each other, the port 14 communicating with the interior of the flask and the port 15 delivering into the outlet chamber 16. A slide 17 fits fluid tight in the guide-way and has a through hole or pocket 6^a, which 65 in one position registers with the port 14, and is out of register with the port 15, while in the other position it is in register with the port 15 and out of register with the port 14. A spring 17 holds the slide in 70 one position, and a pivoted lever handle 18 at the side of the flask will move it to the other position. In the position of Fig. 3 the pocket 6^a is filled; in the position of Fig. 4 it drops its charge. The dropping of the 75 charge is insured by an air passage 19 in the fitting, with which the pocket hole 6^a also communicates when it is in communication with the port 15.

What is claimed as new is:

1. As a new article of manufacture, a dandelion-killer, the same being a hand gardening implement comprising a flask to hold a supply of an agent poisonous to plants, means on the forward end of said implement adapted to be pressed down upon a plant to form a poison administering chamber, the implement being formed with a passage between the interior of the flask and said chamber, and a member fitted to 80 reciprocate in fluid-tight contact in said passage, said member having means to deliver a predetermined charge of the poisonous agent from the flask into said chamber. 85

2. As a new article of manufacture, a dandelion-killer, the same being a hand gardening implement comprising a flask to hold a supply of an agent poisonous to plants, means on the forward end of said implement adapted to be pressed down upon a plant 90

80

100

to form a poison administering chamber, the implement being further formed with a passage between the interior of the flask and the upper end of said chamber, the chamber being enlarged relatively to the passage, and a member fitted to reciprocate up and down in said passage in fluid-tight contact there-

with and provided with a pocket arranged to be carried from an upper position in communication with the supply to a lower position within the enlargement of said chamber to deliver a predetermined charge of the poisonous agent into said chamber.

MAX SCHLING.
